BOOK HOLDER

Thomas E. Wade, Laramie, Wyo.

Application April 26, 1939, Serial No. 270,225

2 Claims.

(Cl. 45—85)

The invention relates to a book holder and more especially to a book stand or book rack.

The primary object of the invention is the provision of a holder of this character wherein a book, for example, a dictionary or other book can be held so that ready reference may be had thereto in that it can be conveniently opened and supported for reference to the same, the holder being of novel construction to enable the same to 10 be placed conveniently at one locality or another as it is portable for this purpose.

Another object of the invention is the provision of a holder of this character wherein different sizes of books can be conveniently held therein and the same easily opened and closed for reference purposes and in this way eliminating the necessity of placing the book upon a support or in the lap of a person, particularly where the book be of large size as for example the large 20 edition of the dictionary or the like.

A further object of the invention is the provision of a holder of this character wherein the construction thereof renders the same serviceable 25 for schools, libraries or the like for the holding of a reference book in a manner to avoid damage thereto resulting from rough handling as is the case in the use of a book of its character and assures ready and quick reference as the occasion 30 may require.

A still further object of the invention is the provision of a holder of this character which is simple in its construction, thoroughly reliable and efficient in operation, strong, durable, neat in 35 appearance and inexpensive to manufacture.

With these and other objects in view, the invention consists in the features of construction, combination and arrangement of parts as will be hereinafter more fully described in detail, illustrated in the accompanying drawings, which disclose the preferred embodiment of the invention 40 and pointed out in the claims hereunto appended.

In the accompanying drawings:

Figure 1 is a perspective view of the holder 45 constructed in accordance with the invention with a book placed therein.

Figure 2 is a side elevation.

Figure 3 is a top plan view.

Figure 4 is an enlarged end elevation showing 50 the holder in normal position and by dotted lines in an adjusted position for the opening of a book held thereby.

Figure 5 is a fragmentary end elevation showing a slight modification.

55 Similar reference characters indicate corre-

sponding parts throughout the several views in the drawings.

Referring to the drawings in detail, A designates generally the book holder or more probably a book stand or rack constructed in accordance 5 with the invention. This construction involves a base frame having substantially U-shaped opposed side members 10 and front and rear or end cross rails 11 and 12 respectively, these being bolted or otherwise made secure to the members 10 to give rigidity to the said frame. The end members are equipped with glider knobs or feet 30. The members 10 are spaced the required distance apart and similarly the cross rails 11 are vertically spaced from the rails 12. The rails 11 15 are uppermost to the rails 12 and in parallel relation thereto.

Arranged within the frame and operating through the open top thereof is an extensible opening and closing saddle for a book comprising 20 an intermediate back rest 14 which is of concavo-convex elongated formation and connected to opposite longer side edges thereof are side cheeks 15, the connections being hinges 16 so that these cheeks can swing arcuately in a vertical direction. The cheeks carry adjustable sections 17 25 for increasing or decreasing the length of the saddle, the book held therein being denoted at 18 and said sections are adjustably bolted at 19 to the cheeks 15 for adjustment. 30

The cheeks 15 and the sections 17 associated therewith are formed at the outermost ends of the said saddle with wings 20 being inwardly directed at right angles to the said cheeks and extensions to eliminate longitudinal displacement 35 of the book 18 when within the saddle. The wings 20 next to the cheeks 15 and the said extension 17 are channeled or grooved at 21 for accommodating the end edges of the binder 22 of the book 18 so that this binder will be interlocked or interconnected with the said cheeks and extensions when the book is confined within the saddle. 40

Formed at opposite ends of the back rest 14 which is extended in close proximity to the vertically arranged guide rods 23 are ears 24, these being slidably fitted with the said rods 23 which are fixedly joined with the rails 11 and 12 and in this manner the saddle is guided in a vertical direction on the opening and closing thereof. 45

Fitted within the frame preferably attached to the vertical limbs 25 of the members 10 are pivot rods 26 being horizontally disposed within said frame and with which are swingingly connected links 27, these being pivoted at 28 to 50 55

brackets 29 fixed exteriorly on the cheeks 15, these being also equipped at the outer faces thereof with grips or handles 30. The saddle can be opened from a normally closed position by pulling outwardly upon the grips or handles 30 causing the cheeks 15 with the extension 17 thereof to swing upwardly and laterally raising the back rest 14 in a vertical direction being guided by the rods 23 and through this manipulation, the book 18 is brought to a raised open position from the normal closed position within the saddle so that ready reference may be had to this book. The links 27 have leverage upon the cheeks 15 and in this manner the saddle will be opened and closed. For the closing of the saddle the cheeks 15 are swung inwardly and concurrently therewith the back rest 14 lowered in the frame being guided by the rods 23 and such saddle will assume the position shown in Figures 1, 2 and 3 of the drawings or the position shown by full lines in Figure 4 while the open position of the saddle being shown by dotted lines in said Figure 4.

In Figure 5 of the drawings there is shown a slight modification of the invention wherein the book saddle has the back rest formed in several sections 31 and 32 respectively. These are disposed in overlapped relation to each other and are provided with registering slots 33 at the overlap for accommodating an adjustable fastener 34 after feeding a tie bar 35 which is slidably engaged with the rods 23. In this manner through the use of the sections 31 and 32 the saddle can be increased or decreased in width for accommodating different sizes or thicknesses of books for the holding thereof.

What is claimed is:

1. A book holder comprising spaced substantially U-shaped opposed side members, front and rear cross rails secured to said side members, glider knobs outstruck from the lower portions 5 of said side members, pivot rods mounted in the side members in the same horizontal plane elevated with respect to the lowermost portions of said side members, a saddle located between the side members and the front and rear rails and 10 having swinging opening and closing cheeks, a back rest, links hinged to the cheeks exteriorly thereof and connected with the pivots carried by the side members, guide rods extending vertically with respect to the front and rear rails, and ears 15 extended from the back rest and slidable on the guide rods.

2. A book holder comprising spaced substantially U-shaped opposed side members, front and rear cross rails secured to said side members, glider 20 knobs outstruck from the lower portions of said side members, pivot rods mounted in the side members in the same horizontal plane elevated with respect to the lowermost portions of said side members, a saddle located between the side 25 members and the front and rear rails and having swinging opening and closing cheeks, a back rest, links hinged to the cheeks exteriorly thereof and connected with the pivots carried by the side members, guide rods extending vertically with 30 respect to the front and rear rails, ears extended from the back rest and slidable on the guide rods, means included in the back rest for extending or contracting the same, and sections adjustably fitted with the cheeks and having wings. 35

THOMAS E. WADE.
